[57] CLAIM

The ornamental design for a football hitch plug, as shown and described,

DESCRIPTION

FIG. 1 is a perspective view of a football hitch plug showing my new design;

FIG. 2 is a top plan view of the football hitch plug and a bottom view of the football hitch plug as the bottom and top views are identical;

FIG. 3 is a right side elevational view of the football hitch plug;

FIG. 4 is a front elevational view of the football hitch plug;
FIG. 5 is a rear elevational view of the football hitch plug; and,

FIG. 6 is a perspective view shown at a reduced scale of the football hitch plug mounted on the hitch of a vehicle.
The broken lines showing a vehicle is for illustrative purposes only and forms no part of the claimed design.
